UNITED STATES PATENT OFFICE.

CHARLES W. CARMAN, OF NEWBURG, WEST VIRGINIA, ASSIGNEE OF ONE-HALF TO
CHRISTIANA CARMAN, OF NEWBURG, WEST VIRGINIA.

MINE-DOOR.

1,240,541.

Specification of Letters Patent. Patented Sept. 18, 1917.

Application filed February 19, 1917. Serial No. 149,635.

To all whom it may concern:

Be it known that I, CHARLES W. CARMAN, a citizen of the United States, residing at Newburg, in the county of Preston and State of West Virginia, have invented certain new and useful Improvements in Mine-Doors, of which the following is a specification.

This invention relates to mine-doors of that type which are adapted to be placed in headings to insure of a circulation of pure air throughout the mine.

The invention more particularly contemplates certain improvements in the structural arrangement and method of operation of the mine-door shown and described in Patent Number 931,035, granted to me on August 17, 1909.

In the use of the door constructed in accordance with the above mentioned patent a number of more or less serious defects manifested themselves which precluded the possibility of this door operating in an entirely successful manner. Principal among these defects was that entirely too great a weight was required to be placed upon the depression rail to raise the door from its lowered position, the cars, when approaching the door, unless being heavily loaded, failing to raise the door quickly and positively, as is necessary. Furthermore, when sufficient weight was applied to operate the door from a lowered to a raised position to permit the passage of the car therethrough, such weight would cause the parts of the apparatus to bind so tightly, particularly the depression rail against the main rail, that the door would not close after the car had passed through the same. These defects in operation were due principally to the faulty arrangement of the levers, rods, etc. for raising the door upon the approach of a car upon the depression rail, and it is, therefore, the principal object of the present invention to not only provide improved means for obviating these defects, as well as others of a lesser degree, but to also generally improve and simplify the entire apparatus.

Among the features of novelty of the invention is the provision of means which may be operated manually, upon stoppage of a car upon the depression rail, for any reason whatever, to permit and cause the door to be moved to a closed position, it being understood that normally the door is held in a

raised position throughout the length of time the car remains on the depression rail. A further feature of novelty resides in the provision of means whereby various parts of the apparatus may be relatively adjusted, 60 thereby providing for its efficient operation under varying conditions of use.

The invention consists in the provision of a door, a depression rail, and lever means arranged so as to raise or lower the door as 65 the rail is depressed or released, and it is another object of the invention to provide means to insure of a smooth operation of the door and levers as the rail is actuated, thereby providing for efficient operation and longevity of the apparatus.

With the foregoing and other objects in view, the invention consists in the novel features of construction, combination and arrangement of parts, as will be hereinafter 75 more fully described, illustrated in the accompanying drawings, and claimed.

In the drawings:

Figure 1 is a side elevation of the invention with parts broken away to either side 80 of the door.

Fig. 1^a is a similar view illustrating the construction to one side of the door in its entirety.

Fig. 2 is a vertical section on the line 2—2 85 of Fig. 1.

Fig. 3 is a vertical section on the line 3—3 of Fig. 2.

Fig. 4 is a fragmentary plan of a portion 90 of the track.

Fig. 5 is a section on the line 5—5 of Fig. 1; and

Fig. 6 is a section on the line 6—6 of Fig. 2.

Referring now to the drawings by numerals, wherein is illustrated the preferred embodiment of the invention, 1 and 2 designate the rails of a track over which the cars carrying the products of the mine travel. As will be understood, the track is arranged 100 in the tunnel of the mine, and the door to be presently described in detail is arranged across the track so as to close the tunnel at all times except when one or more of the cars is to be moved by the same.

The door is made up of a frame comprising side beams 3 and 4 and a post 5, the said beams and post being connected at their upper ends by a cross beam 6, while the beams 3 and 4 are connected at their lower 110

ends by a second cross beam 7 constituting a tie for the rails of the track.

Near their upper ends the beams 3 and 4 and post 5 are provided with alined bearings 8 in which is journaled a shaft 9 which extends transversely over the track and has mounted thereon, between the beams 3 and 4, a roller 10. Carried by this roller is a door 11 in the nature of a curtain, preferably made of canvas or other similar material which is strengthened and stiffened by transverse strips or slats 12. Channel members 13 are secured to the inner faces of the beams 3 and 4 to receive and guide the curtain as it is raised or lowered upon rotation of the roller.

As before stated, the beam 7 constitutes a tie for the rails 1 and 2, the said rails being supported upon the ties 14 and passing between the beams 3 and 4, as is illustrated to advantage in Fig. 2 of the drawings. The board 15, forming the lower edge of the door, is therefore cut away as at 16 to receive the rails when the door is in a lowered or closed position to insure of the same engaging the beam 7 to provide a comparatively tight contact therewith.

Fixed to the shaft 9, adjacent the beam 4, is a sprocket wheel 17 over which passes a sprocket chain 18, the said chain being extended downwardly and passed over a second relatively larger sprocket wheel 19 fixed to a shaft 20 which is journaled in bearings 21 carried by the beam 4 and post 5. The shaft 9 also has fixed thereon a pulley 22 to which is secured one end of a chain or cable 23, the same being relatively long and carrying at its free end a weight 24, the purpose of which will presently appear.

A pair of integrally cast rollers 25 and 26 are fixed to the shaft 20, and the latter has passed thereover a chain or cable 27. This chain is trained over an idler roller 28 suitably carried by the beam 4 and has secured to its free end a weight 29, the purpose of which will likewise appear hereinafter.

The rail 2 is terminated a suitable distance from either side of the door frame, and its continuance from such terminations is provided for by the pair of angle irons 30 and 31 which pass between the beams 3 and 4 and are suitably secured to the ties 14 and beam 7 in facing relation, being spaced and held in such position by the brace members 32. These angle irons not only form a continuation of the rail 2 adjacent the door, but also act as guide members for a depression rail 33 which is arranged between the angle irons and is adapted for vertical movement, the upper edge thereof normally resting above the upper edges of the angle irons. This depression rail is rigid throughout its length and may be made up of a plurality of sections securely riveted together. It is also of slightly less length

than the angle irons 30 and 31 and has pivotally connected thereto, at each end, as at 34, a link 35, the free end of which is provided with a pin 36 riding in slots 37 in the angle irons, adjacent their ends.

At spaced intervals along the rail 33 the same has secured thereto depending members 38 which are connected by links 39 with the outer ends of arms 40, the inner ends of which are fixed to shafts 41 extending to one side of the depression rail and being supported for rotation in bearing members 42 suitably carried by certain of the ties 14. Also fixed to each of the shafts 41 is a lever 43 which rises vertically therefrom and has its upper end pivotally connected to a rod 44. The lever 43 nearest the door is of a greater length than the remaining levers and is provided at its upper end with a plurality of spaced openings 45 in any one of which a pin 46 is adapted to be placed to pivotally connect the rod 44 thereto, the openings providing for adjustment, as will be understood. The remaining levers 43 are adjustable relatively to the rod by reason of the provision of the plates 47 having the plurality of openings 48 therein, through any one of which the pin 49 may be passed.

The chain 27, after being passed over the roller 26, is extended and secured, as by means of the clip 50, to the upper end of the lever 43 nearest the door.

It will be understood that the arrangement of levers and rods is the same to either side of the door so as to operate the same upon the approach of a car from either direction, the only difference being that instead of each of the levers 43 nearest the door upon either side having a chain 27 secured thereto and being provided with a weight, but one of the chains is provided with a weight while the other is directly fastened to the roller 25, the single weight acting as a counterbalance for both sets of levers and rods, due to the fact that both rollers 25 and 26, being cast integral, are rotated upon depression of the rail 33 from either side of the door.

It is thought from the foregoing that the operation of the apparatus will be apparent. As the car approaches the door from either direction and moves up the link 35 onto the depression rail 33 the same is moved downwardly, and through the instrumentality of the links 39, arms 40 and shafts 41, the levers 43 are swung rearwardly, thereby moving the rods 44. As these rods are moved the chains 27 passing over the rollers 25 and 26 cause the same to rotate and impart a rotary movement to the sprocket wheel 19, which transfers such movement to the shaft 9 through the chain 18, the weight 29 insuring of a smooth uniform operation. The roller 10, being fixed to the shaft 9, will accordingly be rotated to wind the cur-

tain thereon to open the door, as will be obvious. As the shaft 9 is rotated the roller 22 winds the chain 23 thereon and raises the weight 24. Thus, when the car passes through the door and leaves the depression rail this weight will act to rotate the shaft 9 in a reverse direction and return all of the parts of the apparatus to a normal position.

5 A hand wheel 51 is mounted on one end 10 of the shaft 9 whereby the curtain may be manually operated, and in order to insure against too great a movement of the curtain to either a raised or lowered position a connecting chain 52 is provided to connect opposite portions of the sprocket chain 18, 15 said chain 52 being adapted for engagement with either of the sprockets 17 or 19.

Should the car for any reason become stopped on the depression rail, which would 20 cause the door to remain open for an undesirable length of time, it is only necessary to remove the pins connecting the clips 50 with the levers 43 to permit the weight 24 to operate the door to a closed position.

25 From the foregoing description taken in connection with the accompanying drawings it is thought that the construction and operation of the improved mine-door will be clearly understood, and while I have herein 30 shown and described one particular embodiment of my invention, I do not wish to be limited thereto, except for such limitations as the claims may import.

I claim:

35 1. An apparatus of the character described, comprising in combination, a track, a roller, a door to be wound upon said roller, a shaft, a roller on said shaft, an operative connection between said shaft and said first 40 roller, and means to be actuated by a vehicle passing over the track for rotating the shaft, said means including a lever and a chain connected therewith and passing over the last roller, removable pins being provided 45 for connecting the chain to the lever, for the purpose set forth.

2. An automatic mine-door, comprising, 50 in combination, a door, a track including a depression rail, a roller upon which the door is adapted to be wound, a shaft, an operative connection between the depression rail and shaft, a lever fixed to said shaft, a rod, an

adjustable connection between the rod and lever, and an adjustable connection between the rod and roller, substantially as described. 55

3. An automatic door for mines, comprising, in combination, a track including a depression rail, a shaft having a roller thereon upon which the door is adapted to be wound, a second shaft, an operative connection between the depression rail and said last shaft, 60 sprocket wheels on said shafts, a sprocket chain connecting said sprocket wheels, and a second chain connecting opposite portions of said sprocket chain, for the purpose set 65 forth.

4. An automatic door for mines, comprising, in combination, a track, a shaft having a roller thereon upon which the door is adapted to be wound, means automatically 70 actuatable by a vehicle passing over the track for operating the door, and a hand-wheel on the shaft whereby the roller may be manually operated.

5. An automatic mine-door, comprising, 75 in combination, a door, a track including a rigid depression rail extending to either side of the door, a shaft having a roller thereon upon which the door is adapted to be wound, a second roller on said shaft, a chain having 80 one end secured to the roller and carrying a weight at its other end, a second shaft, sprocket wheels on each of said shafts, a chain connecting said sprocket wheels, shafts extending to one side of the depression rail, 85 means operatively connecting the depression rail with the shafts, levers carried by said last shafts, rods connecting said levers, rollers on said second shaft, a chain having one end secured to one of said last mentioned 90 rollers and its other end secured to one of said levers to one side of the door, a chain having one end secured to one of the levers to the opposite side of the door and passing over the second roller on said second shaft, 95 and a weight carried by the other end of said last chain.

In testimony whereof I affix my signature in the presence of two witnesses.

C. W. CARMAN.
